Primary Examiner — Susan E Krakower*Assistant Examiner* — Jerry Shiuan-Hua Hsu*(74) Attorney, Agent, or Firm* — McGlinchey Stafford; R. Andrew Patty, II(57) **CLAIM**

The ornamental design for a trailer, substantially as shown and described.

DESCRIPTION

FIG. 1 is a front, left, side perspective view of a trailer in accordance with the present invention;

FIG. 2 is a rear, right, top perspective view of the trailer in FIG. 1;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the various Figures illustrate portions of the trailer that form no part of the claimed design.
